(57) **CLAIM**

We claim an ornamental design for a laser device, as shown and described.

DESCRIPTION

FIG. 1 is a perspective view of a laser device, showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a right side view of the laser device, shown with an optional mounting insert; and,

FIG. 9 is a right side view, shown mounted to a handgun.

The dashed lines are included for illustrating interior and/or environmental structures and form no part of the claimed design.
